UNITED STATES PATENT OFFICE

2,051,379

THERMAL RELAY.

Benjamin W. Jones, Schenectady, N. Y., assignor
to General Electric Company, a corporation of
New York

Application December 29, 1934, Serial No. 759,718

20 Claims. (Cl. 200—122)

My invention relates to protective devices or relays, more particularly to thermal overload relays, and has for an object the provision of a simple and reliable overload relay of this type.

Various types of thermal overload relays have heretofore been proposed for protecting electrical energy translating apparatus such as motors, transformers and the like from overload conditions which subject the component parts of the apparatus to dangerous temperatures. In applying thermal overload protection to apparatus of this type, it is often desirable and sometimes necessary to immerse the overload relay in a body of oil. For example, it is often necessary to locate an electric motor in a hazardous place which is exposed to explosive or corrosive atmospheres, and it is essential in installations of this type that the entire control, including the overload relay, be immersed in oil. Also, in applying thermal overload protection to an oil-cooled transformer, it is desirable that the thermal overload relay be immersed in the body of oil which surrounds the windings of the transformer.

The immersion of the thermal overload relay in a body of oil gives rise to serious operating difficulties, due principally to the fact that when known types of thermal overload relays designed for operation in air are immersed in oil, the normal current rating of the relay may be doubled or more than doubled by the thermal effect of the oil on the relay parts. Such a differential between the normal current rating of a relay when operated in air and when operated in oil is highly undesirable, and considerable need has been found for a thermal overload relay which is satisfactory for oil immersed operations.

In motor applications, such as described above, it is desirable that the thermal relay shall be substantially unaffected by the temperature of the oil bath, and in a transformer installation, it is desirable that the temperature of the immersing oil shall have substantially the same cooling effect upon the relay as it has upon the transformer windings and core. Accordingly, it is a further object of my invention to provide a thermal overload relay of simple construction, the operation of which is independent of ambient temperature conditions to a predetermined degree.

In carrying out my invention in one form, I provide a thermal overload relay comprising a sealed envelope or container of thermal insulating material disposed adjacent an energizing winding adapted to be connected in circuit with the apparatus to be protected. Within the sealed

envelope I provide a closed circuited secondary winding in inductive relation with the energizing winding and a thermo-responsive device intimately thermally associated with the closed secondary winding to be influenced by the heat generated in the secondary winding, the walls of the envelope serving thermally to isolate the enclosed parts. 5

The sealed envelope is evacuated to a predetermined degree of vacuum, depending upon the purpose for which the relay is to be employed. That is, if it is desirable that the relay shall be substantially independent of ambient temperature conditions as in the motor application suggested above, a very high vacuum should be employed, so as substantially to eliminate heat transfer between the relay parts and the ambient oil by conduction or convection. If it is desirable to utilize the relay in an application, such as the transformer application referred to, in which the relay should be affected to a predetermined degree by ambient temperature conditions, the sealed envelope may be only partially evacuated or may contain an inert gas of sufficient pressure so that the thermal effect of the ambient temperature will affect the relay parts in the same degree as the operating parts of the protected apparatus are affected. 25

More particularly, the operating parts of the relay enclosed within the envelope comprise a magnetic core surrounded by a single-turn secondary winding such as a cylindrical conductor, and a bimetallic element secured at one end to the cylindrical conductor, the other end of the bimetallic element being arranged to control a pair of circuit controlling contacts. Suitable control circuit leads extend from the contacts through the walls of the sealed envelope and are hermetically sealed therein. 30

For a more complete understanding of my invention, reference should now be had to the drawing, in which Fig. 1 is an elevational cross-sectional view of a portion of a thermal relay embodying my invention; Fig. 2 is a perspective view of a relay embodying the device shown in Fig. 1, certain parts being broken away; Fig. 3 is a somewhat diagrammatic view of the relay immersed in a body of oil; and Fig. 4 is a partial cross-sectional view of another modification of the device shown in Fig. 1. 40

Referring now to Figs. 1 and 2 of the drawing, I have shown a thermal overload relay comprising a sealed envelope or container 10 preferably formed of glass or similar material having thermal insulating properties, within which is ar- 50 55

ranged a magnetizable core structure comprising an axially extending rod or bolt 11 supporting a magnetizable body comprising a spirally wound strip 12 of magnetizable material, such as iron, 5 and a pair of spaced cup-shaped magnetizable members 13 and 14. It will be observed that the supporting bolt 11 extends through suitable apertures in the cup-shaped members 13 and 14 and that the upper end of the bolt threadedly engages 10 one end of a metallic supporting member 15, the other end of which is suitably fastened by spot-welding to a pair of supporting wires 16 sealed in a wall of the envelope 10. The other end of the bolt 11 is provided with an enlarged head 17 and 15 a washer 18 whereby the bolt serves to maintain the spirally wound portion 12 and the cup-shaped members 13 and 14 in assembled relation. Secured to the cup-shaped member 14 is a leaf-spring 19 arranged to engage a wall of the envelope 10 so as to position the lower end of the core structure relative to the envelope.

Surrounding the spirally wound portion 12, I provide a heating member comprising a cylinder 20 of copper or other suitable conducting material 25 which serves as a closed circuited single-turn winding. The upper end of the cylinder 20 is arranged tightly to engage an enlarged shoulder portion 21 formed on the spirally wound portion 12 in order to provide good thermal conductivity 30 between the core structure and the heating member, and a bimetallic element 22 is directly secured at one end thereof to the lower end of the cylindrical conductor 20 in heat-receiving relation therewith. It will be observed that the fixed 35 end of the bimetallic element 22 is electrically connected to the lower end of the bolt 11 by an L-shaped conductor 23 which extends through a suitable slot 24 in the cup-shaped member 14, and that the upper end of the bimetallic element 22 40 extends into a similar slot 25 in the cup-shaped member 13 and carries a contact 26 normally engaging a cooperating contact 27.

The cooperating contact 27 is supported on one end of a spring arm 28, the other end of which is 45 arranged between a conducting block 29 and a pair of insulating washers 30 supported adjacent the supporting member 15 by means of a pair of screws 31 and 32. An insulating block 33 is provided, as shown, electrically to insulate the supporting member 15 from the screws 31 and 32 50 which threadedly engage the block 29 and serve to maintain the block and the washers 30 in tight engagement with the spring arm 28 fixedly to secure one end thereof. It will be seen that the screw 32 extends outwardly from the block 29 55 through an aperture 34 in the spring arm 28 adjacent its free end and is provided with a headed portion 35 to form an adjustable stop for the spring supported contact 27.

In order that the contacts 26 and 27 may be 60 electrically connected in an external control circuit, I provide a pair of conductor leads 36 and 37 which extend through and are hermetically sealed in a wall of the envelope 10, the end of the lead 36 65 which extends within the container 10 being electrically connected to the supporting member 15 and the end of the lead 37 which extends within the container being connected to the conducting block 29. The circuit through the contacts 26 70 and 27 may be traced from the conducting lead 36 through the supporting member 15, the supporting bolt 11, the L-shaped conductor 23, the bimetallic element 22, the contacts 26 and 27, the spring arm 28 and the conducting block 29 to the 75 conducting lead 37.

Any suitable energizing means may be provided externally of the sealed envelope 10 for producing an alternating flux in the magnetizable core structure within the envelope in order to induce a heating current in the single-turn secondary 20. In the arrangement shown in Fig. 2, the sealed container 10 is disposed in suitable apertures 38 and 39 in the opposite sides of a laminated magnetizable frame 40 which is secured to a suitable base member 41. As will be seen, the lower end 10 of the container 10 rests on a bracket 42 the opposite ends of which are respectively connected to the base 41 and to the frame 40, the bracket 42 being so spaced relative to the frame 40 as to support the container 10 in a position in which the 15 cup-shaped members 13 and 14 within the container are respectively adjacent the opposite sides of the frame 40 whereby the frame provides a plurality of low reluctance magnetic return paths for the core structure within the envelope. A 20 suitable supporting strap 43 having its respective ends connected to the base member 41 is provided for securely holding the upper end of the container 10.

Surrounding the portion of the envelope or container 10 which extends between the sides of the frame 40, I provide a spool 44 of insulating material on which is wound an energizing winding 45 for producing a magnetic flux in the frame 40 and in the magnetizable core structure within the 30 container 10. In some cases it may be desirable to omit the magnetic return paths constituting the frame 40, in which case satisfactory operation of the relay may be obtained merely by increasing the ampere turns in the energizing winding 45, 35 the necessary ratio of increase being in the neighborhood of 2:1.

It will be apparent now that I have provided an improved thermal relay in which the thermal operating parts are thermally isolated by the walls 40 of the envelope 10 so as to be independent of external ambient temperatures to a degree which depends upon the character of the ambient medium within the envelope. The relay is suitable for operation either in air or in an immersing 45 fluid, and in Fig. 3 I have shown somewhat diagrammatically an arrangement in which the base member 41 of the relay is secured to a wall 46 of a tank or casing which contains a body of oil 47.

When my improved thermal relay is to be employed for protecting an energy translating apparatus such as a motor or a transformer, the energizing winding 45 is connected in circuit with the apparatus to be protected and the lead-in conductors 36 and 37 of the relay are connected 55 in circuit with a suitable control device, such as the trip coil of a circuit breaker, arranged to deenergize the apparatus to be protected when the normally closed relay contacts 26 and 27 move to open circuit position. With the energizing winding 45 so connected and normal currents flowing in the protected apparatus, a magnetic flux will be set up in the magnetizable core structure comprising the spirally wound portion 12 and the cup-shaped members 13 and 14 which 65 will induce a heating current in the closed circuited secondary 20. It will be remembered that the portion of the closed circuited heating member 20 which engages the shoulder portion 21 is intimately thermally related to the magnetizable 70 core structure which serves also as a heat storage body and under normal current conditions the heat generated in the secondary member 20 will be conducted to the magnetizable core structure of the relay and will be dissipated therefrom by 75

relay. This feature of my relay is very advantageous since it eliminates the necessity for current transformers which are usually resorted to for supplying current to the ordinary type of thermal overload relay on high voltage installations.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

What I claim as new and desire to secure by Letters Patent of the United States, is:

1. A thermal relay comprising a primary winding, a closed circuited secondary winding disposed therewithin, a thermo-responsive device thermally associated with said secondary winding to be influenced by the heat generated therein and means including walls disposed within said primary winding enclosing said secondary winding and said thermo-responsive device for thermally isolating said enclosed elements.

2. A thermal relay comprising a primary winding, a single-turn secondary winding comprising a cylindrical conductor disposed within said primary winding, a thermo-responsive device thermally associated with said cylindrical conductor to be influenced by the heat generated therein, and means including walls disposed within said primary winding enclosing said cylindrical conductor and said thermo-responsive device for thermally isolating the same.

3. A thermal relay comprising a primary winding, a single-turn secondary winding comprising a cylindrical conductor disposed within said primary winding, a bimetallic element secured to said cylindrical conductor in heat-receiving relation therewith and means including walls disposed within said primary winding enclosing said cylindrical conductor and said bimetallic element for thermally isolating the same.

4. A thermal relay comprising a primary winding, a magnetizable core disposed within and spaced from said primary winding, a closed circuited secondary winding surrounding said core, a thermo-responsive device thermally associated with said secondary winding to be influenced by the heat generated therein and means including walls disposed within said primary winding enclosing said core, said secondary winding and said thermo-responsive device for thermally isolating the same.

5. A thermal relay comprising a primary winding, a magnetizable core disposed within and spaced from said primary winding, a single-turn secondary winding comprising a cylindrical conductor surrounding said core, a bimetallic element secured to said cylindrical conductor in heat-receiving relation therewith and means including walls disposed within said primary winding enclosing said core, said cylindrical conductor and said bimetallic element for thermally isolating the same.

6. A thermal relay comprising a sealed container, an energizing winding adjacent an outer wall of said container, a closed circuited heating winding within said container in inductive relation with said energizing winding, and a thermo-responsive device arranged in heat-receiving relation with said closed circuited winding to be heated thereby.

7. A thermal relay comprising a sealed container, a primary winding disposed around said container, a single-turn secondary winding comprising a cylindrical conductor within said container in inductive relation with said primary winding, and a thermo-responsive device arranged in heat-receiving relation with said cylindrical conductor.

8. A thermal relay comprising an evacuated container, an energizing winding disposed around said container, a single-turn secondary winding comprising a cylindrical conductor within said container in inductive relation with said primary winding, and a bimetallic element secured to said cylindrical conductor to be influenced by heat conducted thereto from said cylindrical conductor.

9. A thermal relay comprising a sealed container, a magnetizable core within said container, a heating member comprising a cylindrical conductor surrounding said core, a thermo-responsive device in heat-receiving relation with said heating member, and means outside said container for producing a magnetic flux in said core to induce a heating current in said heating member.

10. A thermal relay comprising a sealed container, a magnetizable core within said container, a closed circuited heating winding surrounding said core, means including an energizing winding arranged outside said container for inducing a heating current in said heating winding, and a thermo-responsive device in heat-receiving relation with said heating winding.

11. A thermal relay comprising a sealed container, a magnetizable core supported within said container, a closed circuited heating winding surrounding said core, means including a magnetizable member arranged outside of said container having portions disposed adjacent the ends of said core for providing a low reluctance magnetic path between said ends, the walls of said container being interposed between said core and said adjacent portions of said magnetizable member, means including an energizing winding for producing a flux through said core and said magnetizable member whereby a current is induced in said closed circuited heating winding, and a thermo-responsive device within said container in heat-receiving relation with said closed circuited winding.

12. A thermal relay comprising a sealed container, a magnetizable core supported within said container, a heating member comprising a cylindrical conductor surrounding said core, means including a magnetizable member having portions disposed adjacent the ends of said core for providing a low reluctance magnetic return path therebetween, the walls of said container being disposed between said core and said adjacent portions of said magnetizable member, means including an energizing winding for producing a magnetic flux in said magnetizable member and said core to induce a current in said heating member, a bimetallic element within said container in heat-receiving relation with said heating member and circuit controlling contacts controlled by said bimetallic element.

13. A thermal relay comprising a frame of magnetizable material having aligned apertures in opposite sides thereof, a sealed container extending crosswise of said frame disposed in said apertures, a magnetizable core supported within said container with the opposite ends thereof adjacent said opposite sides of said frame, a closed circuited

- winding surrounding said core, means including an energizing winding for producing a magnetic flux in said frame and said core to induce a heating current in said closed circuited winding, and
- 5 5 a thermo-responsive device within said container in heat-receiving relation with said closed circuited winding.
14. A thermal relay comprising a frame of magnetizable material having aligned apertures in opposite sides thereof, a sealed container extending crosswise of said frame disposed in said apertures, a magnetizable core supported within said container with the opposite ends thereof adjacent said opposite sides of said frame, a heating
- 15 member comprising a cylindrical conductor surrounding said core, means including an energizing winding for producing a magnetic flux in said frame and said core to induce a heating current in said heating member, a bimetallic element having one end fastened to said heating member to be heated by heat conducted therefrom and circuit controlling contacts controlled by the other end of said bimetallic member.
- 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770
- strip of magnetic material surrounding said rod between said cup-shaped members, a closed circuited winding surrounding said spirally wound portion of said magnetizable core structure, a thermo-responsive device intimately thermally associated with said closed circuited winding and means for producing an alternating flux through said magnetizable core structure to induce a heating current in said closed circuited winding.
19. A protective device for electrical apparatus; 10 said apparatus having metallic parts and electric conductors thermally related to the metallic parts, said device comprising a sealed container enclosing elements thermally cooperating to produce a resultant thermal characteristic which 15 substantially duplicates the thermal characteristic of the protected apparatus, one of said elements comprising a heat storage body of magnetizable material, another of said elements comprising a closed circuited winding thermally related to said magnetizable body, a thermo-responsive device thermally associated with said closed circuited winding, and means for inducing a heating current in said closed circuited winding 20 proportional to the current in the conductors of the protected apparatus, said magnetizable body, said closed circuited winding and said thermal relation therebetween being proportioned thermally to represent respectively the metallic parts of the apparatus to be protected, the conductors of said apparatus and the thermal relation therebetween, whereby said resultant thermal characteristic is produced.
20. A protective device for electrical apparatus, 25 said apparatus having metallic parts, electric conductors thermally related to the metallic parts and cooling means for dissipating heat from the parts and the conductors, said device comprising an evacuated envelope enclosing elements thermally cooperating to produce a resultant thermal 30 characteristic which substantially duplicates the thermal characteristic of the protected apparatus, one of said elements comprising a heat storage body of magnetizable material, another of said elements comprising a cylindrical conductor surrounding said magnetizable body, portions of said conductor and said magnetizable body being in direct heat-conducting engagement, a bimetallic element secured in heat-receiving relation to said cylindrical conductor, and means for inducing a 35 heating current in said cylindrical conductor proportional to the current in the conductors of the protected apparatus, said magnetizable body, said cylindrical conductor and said thermally engaging portions thereof being proportioned thermally to represent respectively the metallic parts of the apparatus to be protected, the conductors of said apparatus and the thermal relation therebetween, the degree of vacuum within said sealed envelope being proportioned to duplicate the heat- 40 dissipating properties of said cooling means for the apparatus to be protected whereby said resultant thermal characteristic is produced.
